US0D1071664S

(12) **United States Design Patent** (10) **Patent No.:** **US D1,071,664 S**
(45) **Date of Patent:** **** Apr. 22, 2025**

(54) **TUMBLER**

(71) Applicant: **Fiskars UK Limited**, Stoke-on-Trent (GB)

(72) Inventors: **Matthew Kehoe**, Waterford (IE); **Lee Critchlow**, Stoke-on-Trent (GB)

(73) Assignee: **Fiskars UK Limited**, Stoke-on-Trent (GB)

(**) Term: **15 Years**

(21) Appl. No.: **29/928,692**

(22) Filed: **Feb. 14, 2024**

Related U.S. Application Data

(62) Division of application No. 35/516,968, filed on Mar. 14, 2023 (U.S. filing date under 35 U.S.C. 384), and having an international filing date of Mar. 14, 2023, now Pat. No. Des. 1,048,818.
